D. L. LOWERY.
ROTARY ELECTRIC BRUSH.
APPLICATION FILED JUNE 13, 1917.

1,247,849.

Patented Nov. 27, 1917.

UNITED STATES PATENT OFFICE.

DOLPH L. LOWERY, OF SANDUSKY, OHIO.

ROTARY ELECTRIC BRUSH.

1,247,849.

Specification of Letters Patent. Patented Nov. 27, 1917.

Application filed June 13, 1917. Serial No. 174,589.

To all whom it may concern:

Be it known that DOLPH L. LOWERY, a citizen of the United States, residing at Sandusky, in the county of Erie and State 5 of Ohio, has invented certain new and useful Improvements in Rotary Electric Brushes, of which the following is a specification, reference being had to the accompanying drawings.

10 This invention relates to brushes, and particularly to rotary brushes driven by an electric motor.

One of the general objects of this invention is the provision of a brush having a 15 motor upon the shaft on which is mounted a rotary brush, the motor being provided with a frame providing a handle arching over the motor, the frame being provided with wheels so that the brush may be moved 20 over the surface to which it is to be applied in the same manner in which an iron is used in the operation of ironing.

More specifically the objects of my invention are to provide means whereby the dust 25 from the brush may be discharged into a hood and drawn through the hollow handle into a fan housing and from thence discharged into a dust collecting bag.

A further object is to provide a construction 30 of this character which is very compact, in which the parts are evenly balanced, and in which the bag is detachable so that it may be used or not as desired.

Still another object is to provide for a 35 ready attachment and detachment of the bag and for the support of the dust collecting bag when in use.

Another object is to provide means whereby an undue pressure of air may be 40 allowed to escape from the dust collecting bag without carrying the dust with it.

Other objects will appear in the course of the following description.

My invention is illustrated in the accompanying drawings, wherein:—

Figure 1 is a perspective view of my improved brush;

Fig. 2 is a longitudinal sectional view of the brush;

Fig. 3 is a section on the line 3—3 of Fig. 2;

Fig. 4 is a fragmentary sectional view of

the dust collecting bag, the axle 25 being shown in elevation.

Referring to these figures, 10 designates 55 a supporting frame or bed plate, which may be of any suitable construction, and which is provided with the downwardly extending brackets 11, within which are mounted the rollers 12. These rollers may be in the form 60 of caster wheels, if desired, so that they may have a swiveled engagement with the bed plate and thus the machine may be readily shifted in any direction.

Preferably cast in one piece with the bed 65 plate is a metallic housing 13, which is circular in form and is closed by an end plate 14, this housing having an integral handle section 15, which is operatively connected to a second handle section 16, which 70 at its extremity branches from an integral circular fan housing 17.

Mounted upon the bed plate 10 is an electric motor 18, of any suitable construction, the details of which are not shown. The 75 armature 19 of this motor has a shaft which extends into the housing 13, as at 20, and mounted upon this portion of the shaft is a circular brush 21 having radiating bristles or radiating wires, depending upon the pur- 80 pose for which the brush is to be used, as will be later stated. The shaft of the brush is so disposed within the housing 13 that the brush will project down slightly below the open mouth 22 of the housing 13, as illus- 85 trated clearly in Fig. 2. The opposite end of the armature is extended as at 23 into the housing 17 and carries upon it a suction fan 24 having the usual radiating blades.

The housing 17 has a discharge nozzle 25, 90 which extends inward from the housing, that is toward the opposite housing 13, and to one side of the motor. This nozzle is formed with outwardly projecting pins 26 adapted to engage with bayonet slots formed 95 upon the dust bag collar, as will be later described.

The hollow handle section 16 does not discharge directly into the housing 17 but into a duct 27 formed upon the housing 17, this 100 duct leading to a central opening 28 and to the center of the fan, the fan discharging into a lateral branch 29 and out through the nozzle 25. The dust which is drawn from

the brush 21 through the hollow handle thus takes the course shown by the arrows in Fig. 3. The dust is sucked from the brush and through the handle by means of the 5 table suction fan 24 and is discharged out of the nozzle 25.

The dust bag is formed of suitable fabric and is designated 30 and is formed at its open end with a collar 31 having bayonet 10 slots 32, or other suitable means of connecting it to the nozzle 25, so as to have dust tight engagement with the nozzle 25. I do not wish to be limited to any particular means for connecting the dust bag 30 to the 15 nozzle 25. It is obvious, of course, that the bayonet slots 32 coact with the pins 26 in the usual manner. The bag may also be provided at one or more points with outlet nozzles 33 which extend into the bag and are 20 provided on their inner ends with strainers 34 which will permit excess air to pass out from the bag, but prevent dust from passing out.

The bag 30 is held in place upon the bed 25 at one side of the motor 18 by means of the clamps 35 and 36. The clamp 36 is attached to the housing 13, while the clamp 35 is attached to the bed plate. These clamps are curved and are in the form of springs. The 30 motor is held in place upon the bed plate by any suitable means, as for instance by the lugs 37, which extend from the wall of the housing 13 and the housing 17. The motor is connected to the source of current by 35 means of the usual conducting wires 38 and plug 39 and disposed in the circuit of these wires 38 is a switch 40, which is preferably mounted upon the bed plate, the switch, when shifted in one direction, energizing the 40 motor, and when shifted in the other direction cutting off the connection between the motor and the source of energy.

As before stated, the brush 21 may be formed of any desired material, depending 45 upon the use to which the brush is to be put. For instance, if my device is to be used for cleaning billiard tables, clothes, and like articles, then a bristle brush is used, but if the device is to be used for cleaning butcher's 50 blocks, for instance, then wire brushes are used. This construction has been found particularly convenient for cleaning butcher's blocks, as it does away with the necessity of scraping the blocks. The brush may be operated 55 in the manner of an iron and inasmuch as the wheels 12 have swiveled engagement with the bed plate, it is obvious that the brush may be shifted in any direction at the will of the operator. It is also obvious that 60 where the brushes are used for cleaning billiard tables, for instance, it is most desirable that the dust, after being taken up by the brush, shall not be discharged again

upon the table and hence the value of the dust bag. This dust bag may be readily detached and emptied when desired. 65

While I have illustrated a form of brush which I have found thoroughly practical and efficient in every particular, yet I do not wish to be limited to the exact construction 70 illustrated, as many changes may be made therein without departing from the spirit of the invention.

Having described my invention, what I 75 claim is:—

1. A brush of the character described including a wheel supported motor including a shaft, a rotatable brush operatively connected to the shaft at one end of the motor, a rotary suction fan operatively connected 80 to the shaft at the other end of the motor, a housing surrounding the brush, a housing inclosing the fan, and a hollow handle extending over the motor and forming a duct leading from the brush housing to the fan 85 housing.

2. A brush of the character described including a wheel supported motor including a shaft, a rotatable brush operatively connected to the shaft at one end of the motor, 90 a rotary suction fan operatively connected to the shaft at the other end of the motor, a housing surrounding the brush, a housing inclosing the fan, a hollow handle extending over the motor and forming a duct leading 95 from the brush housing to the fan housing, and a detachable dust collecting bag operatively connected to the fan housing.

3. In a brush of the character described, a bed plate, supporting wheels swiveled to the 100 bed plate, a motor mounted upon the bed plate and including a shaft projecting beyond the motor at both ends, a rotatable brush mounted upon one end of the shaft, a suction fan mounted upon the other end of 105 the shaft, a housing inclosing the brush and open at its lower end, a hollow handle extending over the motor and longitudinally thereof, and connecting the brush housing with the fan housing, a dust container operatively connected at one end to the fan housing to receive the dust ejected therefrom. 110

4. A brush of the character described including a wheel supported bed plate, a motor mounted thereon and extending longitudinally thereof and including a shaft projecting beyond the ends of the motor, a rotatable brush mounted upon one end of the motor shaft, a suction fan mounted upon the other end of the motor shaft, a housing 115 inclosing the rotatable brush and open at its lower end, the brush projecting below the open lower end of the housing and said housing being formed with a hollow handle section extending over and longitudinally 120 of the motor, a housing inclosing the suction 125

fan and having an integral hollow handle section extending over the motor and longitudinally thereof and operatively engaging with the first named handle section, the fan 5 housing having a nozzle, and a dust container detachably engaging with said nozzle and supported upon the bed plate.

In testimony whereof I hereunto affix my signature in the presence of two witnesses.

DOLPH L. LOWERY.
